CLAIM

The ornamental design for a motorized eraser, as shown and described.

DESCRIPTION

FIG. 1 is a front perspective view of a motorized eraser showing our new design;

FIG. 2 is a right side elevational view thereof, the left side elevational view being a mirror image thereof;

FIG. 3 is a front elevational view;

FIG. 4 is an end elevational view;

FIG. 5 is an end elevational view opposite that in FIG. 4; and,

FIG. 6 is a rear elevational view thereof.

The eraser portion depicted by means of broken lines in FIGS. 1, 2, 3, and 6 has been shown for illustrative purposes only and forms no part of the claimed design.
